COMBINATION LOCK

Axel Alban J. Carlson, Chicago, Ill.

Application November 15, 1933, Serial No. 698,057

14 Claims. (Cl. 70—127)

The invention pertains to a combination lock especially adapted for use in the prevention of theft of motor vehicles.

The primary object of the invention is to provide a lock of the character indicated embodying an operating element for a switch or other essential control element, and a series of individually operable elements arranged to present a single smooth flat face for coaction with a part on the operating element and adapted only when arranged in a predetermined relation to permit movement of said part and thereby release the operating element for the performance of its intended function.

A further object is to provide a lock having an operating element capable of controlling effectually one or more of the standard control devices employed in motor vehicles and susceptible of manufacture on an economical basis.

Still another object is to provide a combination lock having a plurality of permutation elements with individual dials or like indicating devices capable of being set at will in different relative positions for the purpose of changing the number combination to be employed.

The objects of the invention thus generally stated together with other and ancillary advantages are obtained by the construction and arrangement illustrated in the accompanying drawings forming part hereof, in which:

Figure 1 is a front elevational view of a combination lock having an operating element controlling the ignition circuit of a motor vehicle.

Fig. 2 is a vertical sectional view taken from the plane of line 2—2 of Fig. 1, and showing the operating element in its "locked" position.

Fig. 3 is a fragmentary view similar to Fig. 2, but showing the operating element in its "unlocked" position.

Fig. 4 is a transverse sectional view taken approximately in the line of 4—4 of Fig. 3.

Fig. 5 is a perspective view showing the steering column of an automobile with my improved lock mounted thereon.

Fig. 6 is a fragmentary horizontal sectional view through a steering column with my improved lock mounted thereon and showing a locking bolt for the steering post or shaft controlled by the operating element.

Fig. 7 is a sectional view taken approximately in the plane of line 7—7 of Fig. 6.

Fig. 8 is a view similar to Fig. 7, but illustrating the relation of the operating element to the bolt while withdrawing the latter into an "unlocked" position.

Fig. 9 is a fragmentary sectional view similar to Fig. 8, but showing the operating element held against movement with the bolt in its "unlocked" position.

Fig. 10 is a fragmentary detail view taken approximately in the plane of line 10—10 of Fig. 7.

Referring first to Figs. 1 to 5, I have shown an operating element in the form of a pin 11 mounted centrally of a casing 12 substantially triangular in form, and a series of permutation elements 13, 13^a and 13^b in the form of sleeves arranged concentrically upon the operating element or pin 11. The casing 12 may be made of a main cup-shaped section and a separate rear closure plate 12^a suitably secured in position in the main section.

The sleeves 13, 13^a and 13^b terminate in a single plane perpendicular to the axis of the operating element, being suitably ground to present a smooth transverse bearing face 14 for engagement with a part fixed on the pin. Herein said part is in the form of a lug 15 formed integrally with a collar 16 fast on the pin 11. Preferably, the pin is yieldably urged by means of a spring-coiled expansion spring 17 to hold the lug 15 against the bearing face 14; and to permit of the operation of the pin 11 in performance of its intended controlling function, the sleeves 13, 13^a and 13^b are provided with notches 18, which, when aligned with each other, are adapted to receive the lug 15. Thus, when the permutation elements occupy a predetermined relation, the notches 18 constitute in effect a slot or recess formed in the bearing face 14 adapted to receive the lug 15 and thereby permit of axial movement of the pin 11. The latter has its forward end projecting through the front wall of the casing 12, and for convenience in operating the same, is provided with a knob or button 19.

The means for individually operating the permutation elements 13, 13^a and 13^b comprises in the present instance, three shafts 20, 21 and 22 disposed in spaced relation about the central pin 11 with one shaft in each of the corners of the triangular casing as shown in Fig. 1. These shafts are respectively connected to one of the permutation elements, and to this end each is provided with a spur gear meshing with a spur gear rigid with one of the permutation elements. As shown, the shaft 20 has rigid therewith a spur gear 23 meshing with a gear 24 on the permutation element 13; the shaft 21 has a gear 25 meshing with a gear 26 on the permutation element 13^b; and the shaft 22 has a gear 27 meshing with a gear 28 rigid with the permuta-

tion element 13^a. Each of these shafts has a bearing at its inner end in a plate 29 fixed within the casing 12 adjacent the rear wall 12^a thereof; and the shafts similarly have bearings in the 5 front wall of the casing through which wall the shafts project. Operating knobs 30, 31 and 32 are provided on such forwardly projecting ends of the shafts 22, 24 and 26 respectively, to permit of convenient operation of the several permutation elements. The inner end of the center pin 11 also has a bearing in the plate 29.

It will be seen that by the construction thus provided, movement of the permutation elements into a predetermined relation such that the 15 notches 18 in the bearing face 14 are brought into alignment opposite the lug 15 will permit movement of the operating element or pin 11 axially of the casing; and that such movement of the pin 11 may be utilized in the performance 20 of the intended controlling function, which in the present instance, is the operation of a switch interposed in the ignition circuit.

As shown in Fig. 2, the switch to be controlled comprises a pair of stationary contacts 33 mounted 25 upon a bracket 34 secured on one edge wall of the casing and a movable contact 35 carried by an arm 36 which is rigid with the collar 16. The stationary contacts 33 are interposed in the ignition circuit and the contact 35 is of a length 30 such as to be adapted to bridge said contacts 33 so as to close this circuit. As shown, the ignition wires 35 may be led into the casing 12 through a suitable protecting tube 37 which is preferably made of material which is incapable 35 of being cut readily.

To facilitate the setting of the permutation elements in a desired predetermined combination, each of the operating shafts may be equipped with an indicating device such as a dial 38 adapted for coaction with a suitable point on the face of the casing. This dial 38 is clamped in position upon its shaft by means of its operating knob which may be screw threaded on the shaft and held in position by means of a set screw 39 (Fig. 2). The dial 38 thus clamped is held 40 against rotation relative to the shaft, and this is preferably accomplished by cutting the peripheral edge of the central opening of the disk so as to form a series of teeth 38^a (Fig. 10) adapted to 45 coact with similarly cut teeth in the shaft. By this construction, the operator of a given motor vehicle may readily change the combination to be employed in operating the lock. In effecting this result, the operator will set the permutation 50 elements according to the previous combination so as to permit movement of the lug 15 on the operating element into the aligned notches 18 in the permutation elements, and while the parts are in this relation, remove one or more of the 55 operating knobs 30, 31 and 32 and change the positions of the dials relative to the shafts. The 60 number combination to be employed in the subsequent operation of the lock can then be observed and noted.

In Figs. 6 to 9, I have shown a modified form 65 of the lock applied to the locking of the steering post as well as for controlling the ignition, although it will be understood that the control of either function may be deemed sufficient. In 70 this instance, the lock is adapted to be mounted on the steering column as before, with the center pin 11 parallel with the column. As shown, the casing 12 is for this purpose inserted into a rigid housing 41 having an arm 39 for coaction with a 75 clamping plate 39^a bolted to the head with the

column interposed therebetween. To lock the column, a bolt 42 is provided, movable in a direction radially of the column through one wall of the casing 12 and its housing, and through an aperture 43^a in the column and into a hole 42 in the steering post 43, provided of course, said hole 42 is in position to receive the bolt 42.

To operate the bolt, the center pin 11 is provided with a pinion 44 which, in an axial movement of the pin, as permitted by the proper setting of the permutation elements, is adapted to move into mesh with a rack 45 formed integral with one end of the bolt 42. A coiled expansion spring 46 interposed between the rack 45 and a stationary block 47 in the casing normally urges 15 the bolt in the direction of the steering post.

To withdraw the bolt, the permutation elements must first be set in their proper relation, in accordance with the predetermined combination, whereupon the pin 11 will be permitted to move 20 to carry its pinion 44 into mesh with the rack 45. Subsequent rotation of the pin by the operator will effect the withdrawal of the bolt from its locking engagement with the steering column to free the latter for operation. To hold the bolt 25 withdrawn against the action of the spring 46, an additional axial movement of the pin 11 is permitted by the operator to carry the pinion 44 into engagement with a stationary rack 48, it being understood that in the operation of withdrawing the bolt, the operator will restrain the center pin and hence the pinion 44 from moving into engagement with the holding rack 48.

Where, in addition to the locking of the steering mechanism the ignition switch is to be controlled, 35 the parts are so proportioned that the switch contact 35 is moved into bridging relation with the contacts 33 only in the final portion of the movement of the pin 11 in which the pinion 44 engages with the holding rack 48. Thus, as shown in 40 Fig. 8, when the pinion 44 engages with the rack 45 but not with the rack 48, the switch 33, 35 is in open position; but when the pinion 44 meshes with the holding rack 48, said switch is closed as 45 shown in Fig. 9. It will be also understood that in view of the rotary movement imparted to the pin 11 in withdrawing the bolt, the arm 36 carrying the movable switch contact 35 must be so positioned with respect to the pin as to be disposed 50 opposite the stationary switch contacts 33 when the locking bolt has been completely withdrawn.

It will be observed that the construction employed provides a single bearing face for engagement by a part on the operating element, such that it is impossible to detect, by the rotation of 55 the permutation elements, the positions of the notches 18; and because of the large number of possible combinations which may be employed through the use of a plurality of individually operable permutation elements, unauthorized 60 operation of the lock is effectually prevented. At the same time, the construction employed is exceedingly simple, so that the cost of manufacture 65 is small. Also, the possibility of changing the positions of the dials enables each operator to employ a wholly secret number combination.

I claim as my invention:

1. A lock of the character set forth having, in combination, a plurality of permutation elements comprising a plurality of sleeves arranged in concentric relation and having edges at one end co-operating to provide a flat bearing surface with notches in said end edges adapted to be moved in the rotation of said elements into and out of a registering relation, an operating element mov- 75

- able axially of said permutation elements and having a part thereon adapted to enter said notches in their registering relation, said permutation elements having spur gears at the end opposite said bearing surface, one rigid with each of said sleeves, and a plurality of shafts each having a gear thereon and respectively meshing with one of the gears on said sleeves.
5. A lock of the character set forth comprising, in combination, with the steering column of a motor vehicle and a steering element therein, a casing mounted on said column, an operating element mounted for axial sliding movement in said casing parallel with said column, a plurality of permutation elements mounted in said casing, means in said casing operable from the exterior thereof to position said permutation elements in different relative positions, said permutation elements providing a bearing surface having in one 10 relation of the elements a plurality of alined notches, a part on said operating element adapted to enter said alined notches, and a locking bolt in said casing mounted for movement radially of said column into and out of locking relation to said steering element, said bolt being operatively connected with said operating element when said part is disposed in said notches.
20. 6. A lock of the character set forth comprising, in combination, an axially slidable bolt having a rack bar rigid therewith, an axially slid- 15 able and rotatable operating element having a pinion thereon movable in the axial movement of the operating element into and out of engagement with said rack bar, and a series of permutation elements for governing the axial movement of said operating element.
25. 7. A lock of the character set forth comprising, in combination with a locking bolt and a control switch, an operating element mounted for axial and rotational movement, a series of permutation elements having spur gears at the end opposite said bearing surface, one rigid with each of said sleeves, and a plurality of shafts each having a gear thereon and respectively meshing with one of the gears on said sleeves.
30. 8. A lock of the character set forth comprising, in combination with a locking bolt, a plurality of permutation elements, and an operating member movable in a predetermined relation of said permutation elements into operative 20 relation to said bolt and into engagement with said elements to prevent said elements from being relatively dislodged from said predetermined relation while said member and said bolt are in operative relation.
35. 9. In a lock of the character set forth, the combination of a locking bolt, a plurality of individually adjustable permutation elements having concentric cylindrical portions journaled one upon the other, the end faces of said cylindrical portions together forming a single bearing surface, each of said cylindrical portions having a notch in its end face which upon alinement with the other notches forms a recess, a lug mounted for rotation on the axis of said cylindrical portions and normally restrained from longitudinal movement by said single bearing surface but permitted to move longitudinally when opposite the recess formed by the alinement of said notches, said lug being operatively associated with said locking bolt when said lug is in said recess whereby the locking bolt may be moved only when said lug and said recess are longitudinally alined.
40. 10. A lock of the character set forth comprising, in combination, a casing, a member mounted in said casing for movement in the operation of the lock, a plurality of concentric rotatable sleeves mounted in said casing, means associated with said sleeves at the side thereof for individually adjusting said sleeves, fixed means forming an abutment for said sleeves at one end thereof, the end faces at the other end of said sleeves together forming a single bearing surface shaped in a predetermined relation of said sleeves to provide a recess, a part on said member normally abutting against said bearing surface but adapted to enter said recess to permit movement of said member, and means for holding said part in abutment with said bearing surface.
45. 11. A lock of the character set forth comprising, in combination, a casing, a member slidably supported by the wall of said casing and movable in the operation of the lock, a plurality of concentric sleeves mounted for rotation on said member, said sleeves having radially extending portions at one end for individual adjustment of the sleeves positioned in abutment with one another and with the wall of said casing, the end faces at the other end of said sleeves together forming a single bearing surface shaped in a 50
55. 60
65. 70
75. 75

predetermined relation of said sleeves to provide a recess, a lug normally abutting against said bearing surface but adapted to enter said recess to permit movement of said member, and means 5 for holding said lug in abutment with said bearing surface.

12. A lock of the character set forth comprising, in combination, a casing, a member slidably supported by said casing and movable in the operation of the lock, a plurality of concentric rotatable sleeves mounted in said casing in abutment at one end with one wall of the casing, means for individually adjusting said sleeves and operatively connected to said sleeves at the side 10 thereof, the end faces of the sleeves at the other end thereof forming a single bearing surface shaped in a predetermined relation of the sleeves to provide a recess, a collar rigid with said member and having a lug normally bearing against 15 said surface to prevent movement of said member but adapted to enter said recess to permit movement of said member, and a spring bearing at one end against the opposite wall of the casing and at its other end against said collar to hold 20 said lug in engagement with said surface.

13. A lock of the character set forth comprising, in combination, a control switch comprising a fixed contact and a movable contact, spring 25 means tending to hold said contacts in engage-

ment, a lug movable with said movable contact, and a permutation device controlling movement of said lug comprising a plurality of concentric rotatable sleeves, the end faces of said sleeves together forming a single bearing surface shaped in a predetermined relation of said sleeves to provide a recess for said lug to permit movement thereof, said spring means holding said lug in engagement with said bearing surface when said sleeves are in other than said predetermined relation. 5

14. A lock of the character set forth comprising, in combination, a longitudinally movable spindle, a plurality of concentric sleeves rotatably mounted on said spindle, each sleeve having 10 a notch in one end face adapted in a predetermined relation of said sleeves to be aligned to provide a recess, said end faces together forming a single bearing surface, a lug rigid with said spindle and positioned to engage said bearing 15 surface and to enter said recess when formed, a control switch comprising a fixed contact and a movable contact adapted to engage when said lug enters said recess, and a spring tending to move said spindle longitudinally to hold the contacts 20 in engagement when the lug enters said recess but normally holding the lug in engagement with said bearing surface. 25
